US00D362657S

United States Patent [19]**Tomikawa et al.**[11] **Patent Number:** **Des. 362,657**[45] **Date of Patent:** ****Sep. 26, 1995****[54] VEHICLE POWER ADAPTER WITH VOLTAGE DROPPER**D. 345,960 4/1994 Boyd et al. D13/144
D. 349,096 7/1994 Hyvonen ..... D13/144 X**[75] Inventors:** **Arifumi Tomikawa; Eiichi Ikeda; Masanobu Nakamura**, all of Kawasaki, Japan*Primary Examiner*—Joel Sincavage
Attorney, Agent, or Firm—Foley & Lardner**[73] Assignee:** **Oki Electric Cable Co., Ltd.**, Kawasaki, Japan**[57] CLAIM**
The ornamental design for a vehicle power adapter with voltage dropper, as shown and described.**[**] Term:** **14 Years****DESCRIPTION****[21] Appl. No.:** **32,101**

FIG. 1 is a front perspective view of a vehicle power adapter with voltage dropper showing the new design;

[22] Filed: **Dec. 6, 1994**

FIG. 2 is a front elevation thereof;

[30] Foreign Application Priority Data

FIG. 3 is a rear elevation thereof;

Jun. 17, 1994 [JP] Japan 6-18046

FIG. 4 is a right side elevation thereof;

[52] U.S. Cl. **D13/144; D13/110**

FIG. 5 is a left side elevation thereof;

[58] Field of Search D13/110, 144; 439/638, 668

FIG. 6 is a top plan view thereof; and,

[56] References Cited

FIG. 7 is a bottom plan view thereof.
